UNITED STATES PATENT OFFICE.

CHRISTOPHER BROWN, OF CHARLEROI, PENNSYLVANIA.

EDGE-SMOOTHING MACHINE.

1,415,785.

Specification of Letters Patent.

Patented May 9, 1922.

Application filed May 18, 1918. Serial No. 235,263.

To all whom it may concern:

Be it known that I, CHRISTOPHER BROWN, a citizen of the United States, and a resident of Charleroi, in the county of Washington 5 and State of Pennsylvania, have made a new and useful Invention in Edge-Smoothing Machines, of which the following is a specification.

The invention relates to a machine for smoothing the edges of sheets of material, such as Carrara glass, marble, etc. It has for its principal objects the provision of a smoothing or abrading device of the belt or band type, (1) in which a maximum wear of 10 the belt or band is secured, (2) which is of cheap, simple construction easily repaired and maintained in operating condition, (3) which can be effectively used by an operative after a limited amount of experience, and 15 (4) in which improved means are provided for causing the band to engage the edge of the sheet of material with the necessary smoothing or abrading pressure. One embodiment of the invention is illustrated in 20 the accompanying drawings wherein:

Figure 1 is a side elevation of the machine, Fig. 2 is a plan view of the machine, Fig. 3 is an enlarged section of detail, Fig. 4 is a section on a line IV—IV of Fig. 3, and Fig. 30 5 is a section on the line V—V of Fig. 3.

The abrading element in the device is a band or belt 1 preferably of cloth and having an operating surface of carborundum or other abrading material, belts of this character constituting a well known article of commerce. This belt runs in a vertical plane over three pulleys 2, 3 and 4 mounted in a suitable framework 5. These pulleys have their surfaces covered with leather to 35 give better frictional engagement with the belt and the pulley 2 is driven from a suitable source of power by means of the belt 6. The belt is preferably kept tight by means of a heavy idler pulley 7 mounted upon the lever 8 and provided with a suitable handle 9 for raising the pulley for the removal or application of a belt.

Extending transversely of the front of the machine is a track 10 upon which is mounted 50 a truck or carrier 11 adapted to support the sheet of material whose edge is being smoothed, such sheet being indicated by the reference numeral 12. Transverse bars 13 serve to support the sheet 12, such bars being provided with a series of holes 14 (Fig. 55 2) adapted to receive the pins 15 for holding

the sheet in proper position upon the table.

In order to give the belt 1 the necessary abrading contact with the edge of the sheet being smoothed, the pressure applying device shown in detail in Figs. 3 and 4, is employed. This device comprises a hand lever 16 pivoted at 17 to a bracket 18 carried by the frame of the machine. The connection 17 between the lever 16 and the bracket 60 18 is preferably a relatively loose one, so that the lever can be moved vertically a limited distance back and forth as well as horizontally. The lever carries intermediate its ends the block 19, such block being mounted 65 upon the bolt 20. The front face of this block 19 is preferably rounded as indicated at 21 in Fig. 4 and is provided with the face 22 of yielding material preferably leather.

In operation the lever is moved forward 70 causing the leather face to engage the abrading band or belt and press it against the edge of the sheet 12. While pressure is being applied, the lever is moved up and down about its loose pivot 17 so that pressure is applied 75 from the bottom of the edge of material 12 to the top thereof, thus insuring that the entire width of the edge shall be smoothed. In order to subject the entire length of the edge of the sheet to the abrading action of the belt, 80 the truck 11 is moved slowly back and forth across the band. This series of operations serves to secure the smoothing of the edge of 85 the sheet throughout its entire area.

The features of rounding the edge of the 90 block 21 and of giving the lever its limited vertical movement have been found to be most desirable from a practical standpoint. A too rapid wearing away or grooving of the leather face 22 is avoided, abrading pressure 95 by the belt may be applied on all parts of the edge of the sheet of material being smoothed, and the abrading pressure may be localized because of the restricted area of contact between the rounded leather face and the belt. 100 The belt is also worn out uniformly throughout its width so that a maximum cutting effect is secured from each belt. The machine can be operated cheaply and the operators quickly acquire the skill necessary to 105 operate the machine successfully, one operator accomplishing the work of a large number previously required in the hand smoothing operation heretofore practiced.

What I claim is:

1. In combination in an edge smoothing machine, a sheet support, an endless abrad-

ing or smoothing belt mounted to run transversely of the sheet carried on the support, means for driving the belt, and a presser member back of the belt opposite the edge of the sheet and mounted to move freely toward the belt to press it against the edge of the sheet, and also longitudinally of the belt.

5. In combination in an edge smoothing machine, a sheet support, an endless abrad-

ing or smoothing belt mounted to run transversely of the sheet carried on the support, means for driving the belt, a manually operable member mounted back of the belt for movement toward and from the belt and longitudinally thereof, and a presser block 15 pivoted on said member to permit a limited rocking movement thereon.

CHRISTOPHER BROWN.
